SCARECROW-SHAPED HEAD FOR RECREATIONAL EQUIPMENT

Robert S. Wormser, Hillsdale, Mich., assignor to Game-Time, Inc., Litchfield, Mich., a corporation of Michigan

Filed Mar. 4, 1968, Ser. No. 10,833

Term of patent 14 years

Int. Cl. D21—03, 04, 99

U.S. Cl. D34—4

FIG. 1

FIG. 1 is a front perspective view of a scarecrow-shaped head for recreational equipment in accord with my design, the rear being identical thereto,

FIG. 2 is an elevational side view of the design, the opposite side being identical thereto, and

FIG. 3 is a top plan view.

I claim:

The ornamental design for a scarecrow-shaped head for recreational equipment, substantially as shown and described.
